CLAIM

We claim the ornamental design for a “child-resistant case,”
as shown and described.

DESCRIPTION

FIG. 1 is a front view of a child-resistant case in a closed configuration;

FIG. 2 is a back view of the child-resistant case of FIG. 1;
FIG. 3 is a left side view of the child-resistant case of FIG. 1;

FIG. 4 is a right side view of the child-resistant case of FIG. 1;

FIG. 5 is a top view of the child-resistant case of FIG. 1;
FIG. 6 is a bottom view of the child-resistant case of FIG. 1;

FIG. 7 is a perspective view of the child-resistant case of FIG. 1;

FIG. 8 is a front view of the child-resistant case of FIG. 1 in an open configuration;

FIG. 9 is a perspective view of the child-resistant case of FIG. 1 in an open configuration;

FIG. 10 is an environmental view of the child-resistant case;
FIG. 11 is a perspective view of an alternative embodiment of a child-resistant case in an open configuration;

FIG. 12 is an environmental view of the child-resistant case;
FIG. 13 is a front view of an alternative embodiment of a child-resistant case in a closed configuration;

FIG. 14 is a back view of the child-resistant case of FIG. 13;
FIG. 15 is a left side view of the child-resistant case of FIG. 13;

(Continued)

FIG. 16 is a right side view of the child-resistant case of FIG. 13;
 FIG. 17 is a top view of the child-resistant case of FIG. 13;
 FIG. 18 is a bottom view of the child-resistant case of FIG. 13;
 FIG. 19 is a perspective view of the child-resistant case of FIG. 13;
 FIG. 20 is a front view of the child-resistant case of FIG. 13 in an open configuration;
 FIG. 21 is a perspective view of the child-resistant case of FIG. 13 in an open configuration;
 FIG. 22 is an environmental view of the child-resistant case of FIG. 13;
 FIG. 23 is a front view of a child-resistant case;
 FIG. 24 is a back view of the child-resistant case of FIG. 23;
 FIG. 25 is a left side view of the child-resistant case of FIG. 23;
 FIG. 26 is a right side view of the child-resistant case of FIG. 23;
 FIG. 27 is a top view of the child-resistant case of FIG. 23;
 FIG. 28 is a bottom view of the child-resistant case of FIG. 23;
 FIG. 29 is a perspective view of the child-resistant case of FIG. 23;
 FIG. 30 is a front view of the child-resistant case of FIG. 23 in an open configuration;
 FIG. 31 is a perspective view of the child-resistant case of FIG. 23 in an open configuration; and,
 FIG. 32 is an environmental view of the child-resistant case of FIG. 23.
 Broken lines depict portions of the child-resistant case and form no part of the claimed design.
